By Fisher & Moore, ATTYS.

UNITED STATES PATENT OFFICE.

PHILIP P. NUNGESSION, OF CLEVELAND, OHIO, ASSIGNOR TO THE NUNGESSION ELECTRIC BATTERY COMPANY, OF CLEVELAND, OHIO, A CORPORATION.

DESIGN FOR A CARBON ELECTRODE.

42,947.

Specification for Design.

Patented Aug. 27, 1912.

Application filed May 22, 1911. Serial No. 628,862. Term of patent 14 years.

To all whom it may concern:

Be it known that I, PHILIP P. NUNGESSION, a citizen of the United States, residing at Cleveland, in the county of Cuyahoga and State of Ohio, have invented a new, original, and ornamental Design for Carbon Electrodes, of which the following is a specification, reference being had to the accompanying drawing, forming part thereof.

Figure 1 is a side view, Fig. 2 is a top end view, and Fig. 3 is a bottom end view

of a carbon electrode, showing my new design. Fig. 4 is a side elevation viewed at right angles to Fig. 1.

I claim:

The ornamental design for a carbon electrode, as shown.

PHILIP P. NUNGESSION.

Witnesses:

E. M. FISHER,

R. B. MOSER.
